UNITED STATES PATENT OFFICE.

CHARLES M. COFFMAN, OF GALLIPOLIS, OHIO.

AUTO JACK.

Application filed July 14, 1927. Serial No. 205,569.

The present invention relates to jacks or lifting devices adapted particularly for use on automobiles, and has for an object to provide a jack, which is capable of practically complete control in both raising and lowering the mechanism, so that the load may be raised and lowered with ease and at all times be under the control of the operator.

Another object of the invention is to provide a jack for use with balloon tires, or a jack which is capable of hoisting through considerable height and which has an axle support or rest so peculiarly combined with the structure of the jack that the rest may engage under a relatively low axle and raise the same without requiring a reduction in the size of the parts of the jack.

A further object is to provide a jack which has a base and a lifting post, which are relatively small and at the same time strong and durable and which is provided with controlling means mounted on the base and engaging the lifting post, so that the latter may be raised intermittently through some distances, where the post may be locked at any desired height, and wherein the post may be lowered gradually and intermittently or where the post may be released and dropped suddenly.

The invention also aims at the provision of a jack which possesses the above enumerated characteristics, and which at the same time is provided with controlling mechanism operable from the position of the person working the jack, and wherein the handle is utilized not only for a reciprocating motion, but also for a turning motion, and wherein an additional operating means is employed, such as a pull rope.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side elevation of a jack constructed according to the present invention, the handle being broken away and the jack adjusted in position about to raise a load.

Figure 2 is a horizontal section taken through the upper portion of the jack substantially on the line 2-2 of Figure 1.

Figure 3 is a fragmentary side elevation of the upper portion of the jack showing the

lifting post in slightly raised position and showing the handle and operating parts in full and dotted line positions for lowering the lifting post.

Figure 4 is a fragmentary side elevation of the extensible and detachable handle for the jack, showing the pawl releasing cam on the inner end of the handle.

Figure 5 is a fragmentary side elevation showing a modified and preferred form of the stand or shell of the jack, and

Figure 6 is an inner edge view of the same.

Referring to the drawings, 10 designates a hollow upright stationary portion or base having a foot piece 11 suitably shaped to seat upon the ground or roadway to support the base 10 in upright position.

The base 10 is hollow and opens through its upper end, and at its outer edge is provided with a vertical slot 11^a, which opens downwardly from the upper end of the base 10 for receiving a rest 12, which projects from the outer edge of a lifting post 13 disposed for vertical sliding movement in the base 10. A second rest 14 is provided in the shape of a head upon the upper end of the post 13, so that an axle, a spring or other part of an automobile may be seated upon either the rest 12 or the rest 14, and the jack operated to lift the vehicle. The lifting post 13 is provided at its inner edge with a longitudinal row of teeth 15 providing a rack bar with which meshes a pinion 16 fixed on a shaft 17, which has bearing in a pair of spaced lugs 18, which constitute part of the base 10 and extend in an edgewise direction therefrom.

The shaft 17 also carries a ratchet wheel 19, which is relatively large as compared with the pinion 16, and which extends into the base 10 at one side of the lifting post 13, the base 10 having a lateral enlargement 20 at one side to accommodate the ratchet wheel 19. The ratchet wheel 19 has its teeth facing in an anti-clockwise direction, so that when the post is elevated the remote side of the ratchet wheel 19 must be operated downwardly or in a clockwise direction. The shaft 17 provides a pivot or support for a handle 21, which is forked at its inner end and pivoted thereat on the shaft 17. Pivoted in the bight of the handle 21 is a pawl 22 mounted on a transverse bolt 23, which passes through the handle 21, the pawl 22 extending downwardly from the handle and toward the ratchet wheel

19, so as to interlock with the teeth thereof, as shown in Figures 1 and 3. The pawl 22 is substantially S-shape with its inner end extending upwardly from the handle 21 and being curved or over-turned to extend in a lengthwise direction over the handle. The pawl 22 is, therefore, provided with an operating arm 24 disposed above the handle 21. The arm 24 is normally urged to swing downwardly against the handle 21 by a weight 25, which may be integral with the free end of the operating arm 24 or be secured thereto. The handle 21 may be of any suitable length, but is preferably relatively short as it forms a permanent part of the jack and is adapted to be swung close into the side of the jack, so that the latter will occupy but small space. The handle 21 is provided with a reduced shank 26 co-axially disposed upon the outer end of the handle 21, and which is preferably located directly beneath the weight 25. An extension handle is employed, the same shown in Figure 4, and comprising a sleeve or tube 27 of suitable length provided with a bayonet slot 28 in each end, and the shank 26 is provided with a radially extending pin 29 adapted to enter and be interlocked in the bayonet slot 28. The extension handle is also provided with a rod section 30 adapted to enter the end of the sleeve or tube 27, and which carries a radially extending pin 31 also adapted to be interlocked in one of the bayonet slots 28. The rod 30 has the pin 31 preferably on one end only, so that when the jack is not in use the rod 30 may be inserted through the tube 27 with the end bearing pin 31 rearmost so that the pin 31 may be located in the adjacent bayonet slot 28 to hold the rod 30 within the tube 27.

One end of the tube 27 is provided at one side with a lifting cam 32. The cam 32 is so positioned upon the tube 27 that when the tube is mounted on the shank 26 the cam 32 is disposed immediately beneath the pawl arm 24, so that when the handle extension or tube 27 is turned upon the shank 26 the cam 32 is brought into position to engage beneath the arm 24 and raise it. The circumferential portion of the bayonet slot 28 is so disposed as to be substantially co-extensive with the cam 32, and the pin 29 in the shank 26 is so located with respect to the arm 24 as to insure the correct positioning of the cam 32 to one side of the arm 24 as to insure the correct positioning of the cam 32 to one side of the arm 24 as the handle extension is connected to the handle. The definite location of the pin 29 also insures the correct positioning of the cam 32, so that the handle extension need be turned only through a relatively short distance to bring the cam 32 in the full operating position and to release the cam from the weighted arm 24.

The lower portions of the lugs 18 carry a transverse pin 33 upon which is pivotally mounted and located between the lugs 18, a locking pawl 34 whose nose projects inwardly and upwardly for interlocking engagement with the teeth of the ratchet wheel 19 at such an angle as to normally direct the weight and stress imposed upon the ratchet wheel 19 in a straight line to the pivot 33. The locking pawl 34 is normally held in this position by a relatively long weight arm 35, which may be enlarged or otherwise suitably provided with a weight 36 upon its free end. It will be noted that the arm 35 is relatively long and extends downwardly as far as is practical in order to obtain considerable leverage for operating the pawl 34 from a rope 37 or other suitable means for swinging the arm 34 inwardly away from the base 10.

When it is desired to use the jack in raising a load, the load is placed upon the rest 12, or the rest 14. The handle extension is placed upon the handle 21 and adjusted so that the cam 32 is at one side so as to free the arm 24 and permit it to urge the pawl 22 into engagement with the teeth of the ratchet wheel 19. The handle 21 is now swung upwardly into the position shown in Figure 1. The rope 37 is left slack so that the arm 35 is free to swing toward the base 10 and urge the locking pawl 34 into engagement with the teeth of the ratchet wheel 19. The handle 21 when in raised position is interlocked with the ratchet wheel 19, as shown in Figure 1, and the handle is now swung downwardly upon the shaft 17 as a pivot with the result that the ratchet wheel is turned in a clockwise direction and pinion 16 is turned therewith and causes the lifting post 13 to slide upwardly in the base 10.

When the handle 21 reaches its lowermost position the locking dog or pawl 34, by its arm 35, is automatically forced into engagement with the teeth of the ratchet wheel 19, so as to hold the latter from turning in a backward direction and the pawl 34, therefore, supports the lifting post 13 in elevated position. The handle 21 is now raised and the pawl 22 freely slides over the teeth of the ratchet wheel until a new raised position of the handle is obtained. If desired, the handle extension may be turned to operate the cam 32 to lift the arm 24 and withdraw the ratchet 22 from the ratchet wheel 19 as the handle is raised. This operation will save wear between the ratchet wheel and the ratchet.

When it is desired to lower the load from a raised position, the handle 21 is swung into a lowered position and with the pawl 22 in engagement with the ratchet wheel 19. The handle is now firmly held and the rope 37 is drawn taut to swing the arm 35 and release the locking pawl 34 from the

ratchet wheel 19. It may be necessary to force the handle 21 downwardly to a slight extent in order to assist in releasing the locking pawl 34 as such movement of the handle 5 relieves the weight from the pawl 34. The arm 35 is held in an outwardly swung position, as shown in Figure 3, until the handle 21 is raised into substantially the position shown in Figure 3, whereupon the locking 10 pawl 34 is released so as to interlock with the ratchet wheel 19 and hold the load in its new position. The cam 32 is now brought into play by twisting the handle extension, so as to release the pawl 22 from the ratchet 15 wheel, so that the handle 21 may be swung downwardly for a new interlocking grip upon the ratchet wheel 19. When the locking pawl 34 releases the ratchet wheel 19 the load immediately tends to turn the 20 ratchet wheel and raise the handle 21, so that the handle is utilized in controlling the dropping of the load.

If it is desired to quickly release the load, the rope 32 is drawn taut to release the locking pawl 34, and at the same time the handle extension is twisted to bring the cam 32 against the arm 24, so that the pawl 22 is also freed from the ratchet wheel 19. The load pressing downwardly upon the lifting 30 post 13 is now free to force the lifting post down and turn both the pinion 16 and the ratchet wheel 19 without any restrictions.

In the form shown in Figures 5 and 6, the hollow base or stand 10^a is short so as 35 to fit beneath a spring or axle of a vehicle and permit the use of a relatively large pinion and ratchet. In this instance the lateral enlargements 20^a are substantially tangent to the top of the stand and the 40 depending lugs extend below the circular perimeter of the enlargements 20^a.

The remaining parts mounted in the stand 10^a are identical with the showing in Figures 1 to 4 inclusive. The form shown in 45 Figures 5 and 6 is relatively low and is particularly adapted for use with small cars equipped with balloon tires.

It is obvious that various changes and modifications may be made in the details of 50 construction and design of the above specifically described embodiment of this invention without departing from the spirit thereof, such changes and modifications being restricted only by the scope of the following 55 claims.

What is claimed is:—

1. A lifting jack comprising a base, a sliding post mounted in the base and having 60 a rack bar in one edge, a transverse shaft mounted at said edge of the base, a pinion on the shaft meshing with the rack bar, a ratchet wheel mounted on the shaft and connected to the pinion for turning therewith and having its teeth disposed in an anti-clockwise direction, a locking pawl carried

by the base and having a weight arm for normally urging the pawl into interlocking engagement with said ratchet wheel, a handle pivoted upon the base concentric to said ratchet wheel, a pawl pivotally mounted on 70 the handle for interlocking engagement with the ratchet wheel and having a weight arm extending lengthwise of the handle for normally urging the pawl into interlocking engagement with the ratchet wheel, and a 75 handle extension mounted on said handle for reciprocating the same and adapted to be turned, said handle extension having a cam thereon for engagement beneath the weight arm of said pawl on the handle to release the 80 latter from the ratchet wheel.

2. A lifting jack comprising a base open through its top and having a vertical slot opening downwardly from said top and in one edge, a lifting post slidably mounted in 85 the base and having an edgewise projecting rest adapted to enter said slot when the lifting post is lowered, said lifting post having a rack bar in its opposite edge, a transverse shaft mounted in the base, a pinion on said 90 shaft meshing with said rack bar, a ratchet wheel carried by the shaft to turn with the pinion, a handle pivoted on the base, a pawl mounted on the handle and having a weight arm normally urged toward the handle for 95 interlocking the pawl on the handle with said ratchet wheel, a handle extension rotatably mounted on the handle and having a cam at one side adapted for engagement beneath said weight arm of the pawl to release 100 the pawl from the ratchet wheel, and a locking pawl mounted upon the base and having a weight arm normally urging the pawl for 105 interlocking engagement with said ratchet wheel, said weight arms adapted to be raised 110 for releasing both of said pawls from the ratchet wheel to free the same.

3. A lifting jack comprising a base, a lifting post slidably mounted in the base and having rack teeth in one side, said base having a pair of lugs projecting from said side, a shaft mounted in the lugs, a pinion on said shaft meshing with the rack bar, a ratchet wheel on the shaft for rotation with the pinion and projecting into the base at one 115 side of said lifting post, a handle pivoted on said lugs, a pawl pivotally mounted in the handle for engagement with the ratchet wheel and having a weight arm extending outwardly along the handle for normally 120 urging the pawl toward the ratchet wheel, a handle extension detachably and rotatably mounted on the handle and having at one side a cam adapted to be raised beneath the weight arm to free said ratchet upon the turning of the extension handle, a locking pawl pivotally mounted between said lugs beneath the ratchet wheel and having a depending weight arm normally urged toward 125 said base for holding the locking pawl in 130

engagement with the ratchet wheel, and operating means connected to the weight arm of the locking pawl for extension with the handle extension whereby the operations 5 of the pawls may be controlled from a distance remote from the base.

4. A lifting jack comprising a hollow base open at its rear edge and provided with lateral enlargements of circular form disposed at substantially a tangent to the top of the base and projecting from the open edge thereof, said circular enlargements having depending apertured lugs at their lower sides forming extensions of the open

edge of the base, a lifting post in the base 15 having rack teeth at its rear edge; a shaft mounted in said enlargements, a pinion on said shaft meshing with the rack teeth, a ratchet wheel carried by the shaft, a handle pivoted on the shaft, a pawl on the handle 20 having a weighted arm normally interlocking the pawl with the ratchet, and a locking pawl pivotally mounted in said lugs and biased for engagement with said ratchet:

In testimony whereof I affix my signature. 25

CHARLES M. COFFMAN.
